UNITED STATES PATENT OFFICE.

ESTA F. CULBERTSON, OF SEATTLE, WASHINGTON, ASSIGNOR OF ONE-HALF TO
ALEXANDER CHRISTIE, OF SEATTLE, WASHINGTON.

HASP-FASTENER.

1,105,886.

Specification of Letters Patent.

Patented Aug. 4, 1914.

Application filed December 11, 1913. Serial No. 805,886.

To all whom it may concern:

Be it known that I, ESTA F. CULBERTSON, citizen of the United States, residing at Seattle, in the county of King and State of Washington, have invented a certain new and useful Improvement in Hasp-Fasteners, of which the following is a specification.

My invention relates to improvements in hasp fasteners and particularly to improvements in hasp fasteners that are adapted to maintain in a closed position a pair of doors which are disposed within the frame of a single doorway, and the object of my improvement is to provide a strong and simply constructed latch that shall unite and securely hold in a closed position the two doors of a pair of doors mounted in a single door frame, as, for instance, the pair of doors that is employed to close the rear end of a covered delivery wagon such as employed by mercantile houses for the delivery of merchandise and a further object of my improvement is to hold such pair of doors in such tightly closed position as will effectively prevent a rattling or vibration of the doors irrespective of any wear of the latch or looseness of its parts. I accomplish these objects by devices illustrated in the accompanying drawings in which—

Figure 1 is a view in front elevation of my latch as it appears when latched, Fig. 2, is a plan view, on a reduced scale, of the same when associated with a pair of doors and as it may appear when it is unlatched; Fig. 3, is a plan view of the same showing the parts in a latched position and Fig. 4, is a view in perspective of a detail of my invention.

Referring to the drawings, in which like reference numerals indicate like parts, 5 and 6 indicate a pair of doors which may be hinged at their outer side edges and adapted to close, as illustrated in Figs. 2 and 3, against any suitable stop as a door frame or a block 7.

A flat strip 8, of suitable metal, as spring steel, is formed to have its two end portions lie in planes that are at a slight angle to each other, as more clearly illustrated in Fig. 4, one of such end portions being provided with holes 9, 9 through which rivets or bolts 10 and 11 respectively, may extend to secure said strip 8 to a door, as illustrated in Fig. 2, the bolt 11 being formed with a head or lug 12 which is disposed to project

outwardly from the outer surface of the strip 8 and which lug 12 is provided with a hole 13.

A flat bar 14 is provided with an enlarged perforated end portion 15 by which said bar 14 is hinged to a U-shaped bolt bracket 16 which pivotally secures the bar 14 to the door 6, as illustrated in Figs. 2 and 3, such bar 14 being provided at its other end with a slot 17 that is adapted to fit over the lug 65 12 of the bolt 11.

A hook shaped member 18 is pivotally secured to the bar 14 by a rivet or bolt 19 and is adapted freely to be turned in a plane that is parallel with the bar 14, such hook 18 being provided with a handle 20 by which it may be turned and being adapted to have its outer hook shaped end thrust through the perforation 13 in the lug 12 of the bolt 11, as illustrated in Figs. 1 and 3, to fasten securely the doors 5 and 6 together, as shown in Fig. 3.

A hole 21 is provided in the extreme end portion of the hook 18 whereby a padlock may be attached to lock the latch in its 89 closed position.

The bar 14 which is hinged to the door 6 by the U shaped bolt 16 is adapted freely to swing outwardly to permit the doors 5 and 6 to be opened and the bar 8 is rigidly secured to the door 5 by the bolts 10 and 11, the free end portion of such bar 8 normally lying in a plane that is at an angle to the plane of the doors 5 and 6, as illustrated in Fig. 2, to adapt such bar 8 to act as a spring. 90

In the operation of closing the doors 5 and 6, the door 6 is first closed and then the door 5 is closed and thereupon the bar 8 will overlap the door 6. The bar 14 is then swung into the position shown in Fig. 2, in 95 which position such bar 14 will engage with the end of the bar 8 and then a continued inward movement of the bar 14 will overcome the spring force of the bar 8 thus tending to straighten such bar 8 as illustrated in Fig. 3, wherein the bar 14 is shown to be pressed tightly against the bar 8 and there secured by hook 19 which projects its hooked end downwardly through the hole 13 in the lug 12. 100

Obviously the spring like bar 8 exerts a constant pressure against the bar 14 and serves to keep the doors tightly closed and to prevent any rattling of the doors and the parts of the latch. 110

When the doors are to be opened the handle 20 may be grasped and pressure may be exerted thereon to press the member 14 inwardly and at the same time a lifting or twisting force is exerted to raise the hook 18 upwardly into a position as shown by broken lines in Fig. 1, as soon as the hook 18 is free from the lug 12 the bar 8 will spring outwardly into the position shown in Fig. 2 and the bar 14 may be swung backwardly to permit the doors freely to open.

If it be desired to use my latch in connection with a single door the bar 14 may be hinged to the door frame, in the same manner that such bar 14 is hinged to the door 6, thus, it is manifest that my latch is adapted to be used in connection with either single or double doors and, obviously, changes may be made in forms and dimensions of its several parts without departing from the spirit of my invention:

What I claim is:

1. A door latch comprising a latch-bar adapted to be pivotally secured at one end to a support and provided at its other end with an opening, a hasp-hook pivotally se-

cured to said latch-bar to swingingly turn thereon, of an eye-bolt whose eye portion is adapted to project through said opening to engage with and be secured by said hasp-hook, a flat spring adapted to be associated with said eye-bolt and to be disposed so that one of its ends may engage with and press against the pivoted end portion of said latch-bar.

2. A door latch comprising a latch bar adapted to be pivotally secured at one end to a support, a spring member secured to another support and disposed so that one portion of it may engage with and press against the inner surface of said latch bar and means for releasably securing the free end of said latch bar to said last named support.

In witness whereof, I, hereunto subscribe my name this 1st day of December A. D., 1913.

ESTA F. CULBERTSON.
